CLAIM

The ornamental design for a cargo restraint device, as shown.

DESCRIPTION

FIG. 1 is a perspective view of a cargo restraint device of the present invention;

FIG. 2 is a front elevational view of the present invention; FIG. 3 is a right side elevational view of the present invention;

FIG. 4 is a rear elevational view of the present invention;

FIG. 5 is a top view of the present invention; and,

FIG. 6 is a bottom view of the present invention.
